CLAIM

I claim the ornamental design for a wide mouth straw lid, as shown and described.

DESCRIPTION

FIG. 1 is a perspective view of a wide mouth straw lid showing my new design;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof; and,

FIG. 8 is a perspective view of the wide mouth straw lid of FIG. 1 shown in a closed position.

The broken lines depict portions of the wide mouth straw lid that form no part of the claimed design.

1 Claim, 8 Drawing Sheets
